CLAIM

The ornamental design for a circular connector, as shown and described.

DESCRIPTION

FIG. 1 is a right perspective view of a circular connector, showing our new design;

FIG. 2 is a front elevation view thereof;

FIG. 3 is a rear elevation view thereof;

FIG. 4 is a left side elevation view thereof;

FIG. 5 is a right elevation view thereof;

FIG. 6 is a top plan view thereof;

FIG. 7 is a bottom plan view thereof; and,

FIG. 8 is a left perspective view thereof.

The broken lines depict portions of the circular connector that form no part of the claimed design.

1 Claim, 8 Drawing Sheets
